UNITED STATES PATENT OFFICE

FRANK BITTINGER POST, OF MINNEAPOLIS, MINNESOTA, ASSIGNOR TO STEINER SALES COMPANY, OF SALT LAKE CITY, UTAH, A CORPORATION OF UTAH

DESIGN FOR A TOWEL CABINET

Application filed May 16, 1932. Serial No. 43,821. Term of patent 14 years.

To all whom it may concern:

Be it known that I, FRANK B. POST, a citizen of the United States, residing at Minneapolis, in the county of Hennepin and State of Minnesota, have invented a new, original, and ornamental Design for a Towel Cabinet, of which the following is a specification, reference being had to the accompanying drawing, forming part thereof.

The figure is a perspective view of a towel cabinet showing my new design.

I claim:

The ornamental design for a towel cabinet, as shown.

Minneapolis, Hennepin County, Minnesota,
May 10, 1932.

FRANK BITTINGER POST.
